UNITED STATES PATENT OFFICE.

ANATOLE C. HEINY, OF RIDGEFIELD PARK, NEW JERSEY.

ELECTROMAGNETICALLY-OPERATED PUMP.

Application filed February 2, 1924. Serial No. 690,155.

This invention relates to pumps having a reciprocatingly actuated piston by means of which liquids are raised from a lower to a higher level; or when a vacuum is created in a vessel; or air or a gas is compressed in any given container, any of these various actions taking place between two or more check-valves.

My pump differs from all these pumps in 10 the novel feature that its actuating piston actuates a column of mercury which is in-constant contact with it, and descends and rises with it with every one of its downward or upward strokes.

15 A further feature is that the actuating piston is operated by purely magnetic means, it being in fact the internal iron core of an electro-solenoid which, itself, serves as the pump body or pump cylinder.

20 One object in devising this new pump was to produce a pump that would not only be of the most simple construction, but should at the same time be of the greatest efficiency, and be able to work at great speed yet 25 having actual resiliency in every one of its piston strokes, which resiliency is absolutely absent in any and all existing power actuated piston pumps, unless provided with specially constructed devices for absorbing the 30 so-called hammer strokes.

My pump is therefore valuable not only for pumping liquids, but from its construction it will be seen that it is most efficient as a vacuum pump.

35 The nearest approach to an absolute vacuum is the Torricelli, or barometric vacuum. This nearly perfect vacuum no piston pump however accurately or perfectly constructed will ever attain and can only approach after 40 prolonged, and therefore costly, operation. Furthermore, pumps such as these, on account of their accurate construction, can only be operated relatively slowly, whereas the action of my pump is always rapid and 45 its speed regulatable. As a vacuum pump it will therefore be very valuable for laboratory work, in refrigerating plants, for steam power houses as condensing pumps, in the manufacture of electric incandescent lamps, 50 and in fact in any industry requiring either the production of a vacuum, or the compression of gases.

Moreover, my pump is particularly avail-

able for use on automobiles and other vehicles having internal combustion engines, 55 for raising the fuel oil from the generally low level placed main fuel tank, to either the higher level placed carburetor, or to an intermediate gravity tank. Also, on the same vehicles, and in fact in all cases where 60 continuous and automatic lubrication is required, my pump may be used as an oil pump. Furthermore, two of my pumps may be joined and made to act as a duplex pump, 65 and in such case can take the place of the well known duplex pumps generally used for boiler feeding, etc, in my duplex-pump, each pump at the end of its stroke automatically cutting off its electro-magnetic power and shifting it to the other one, and vice- 70 versa.

In the accompanying drawings Fig. 1 shows my pump in vertical central sectional elevation; Fig. 2 is a plan view of the rotary mechanical make and break shown in 75 Fig. 1, to alternately energize and deenergize the solenoid; Fig. 3 is a vertical sectional elevation of the upper parts of two of my pumps set up as a duplex pump, and showing one of the various methods by 80 which each pump breaks its energizing current and shifts it to the other pump; Fig. 4 is a plan view of the pipe connections of 85 a duplex pump; Fig. 5 is a sectional view on line 5—5 of Fig. 6 of a double rotary 90 mechanical make and break device by which a duplex pump may be operated; Fig. 6 is a longitudinal sectional view of the same on line 6—6 of Fig. 5; and Fig. 7 is an enlarged circumferential view of the same.

In Fig. 1, the solenoid S is of the usual construction, i. e., made of a given number of coils 10, wound in the usual manner, but instead of around a non-conducting or dielectric tube, they are preferably wound 95 around a tube 11 of non-magnetic metal or material which is also non-amalgamable by mercury, or the metal or material may be coated in any well known manner with a suitable enamel for rendering the metal or 100 material nonmagnetic and preventing the amalgamation. Tube 11 is set tightly and nonleakably into a base 12 made of iron. Base 12 may be considered as constituting the fixed end armature of solenoid S. Base 13 105 has a downwardly extending hub 13

threaded internally to receive an upwardly extending iron tube 14, and a downwardly extending iron pipe connection 15 by which it is connected to a four-way iron union or double T 16.

The plunger core of the solenoid may be a plain hollow iron cylinder 20, of magnetic metal, Swedish iron preferably, on account of its recognized greater magnetic permeability, and preferably constructed as shown, with a flange 21 and an upper dome-like extension 22 for reasons later stated.

The two leads 30 and 31 of the solenoid are connected respectively to a battery B 15 and a switch s. The other side of the battery is connected to a rheostat R. Between the rheostat and the switch is located a rotary mechanical contact make and break device, which may be made of any design, but 20 which I make preferably as shown in Figs. 1 and 2 of an insulating tube 40 fixedly set on a rotating shaft 41. Tube 40 is covered by a metal tube 42 having a number of longitudinal cuts filled up by relief strips 43, 25 which are parts of tube 40. Two spring contact brushes 44 and 45 are located diametrically opposite one another and in continuous contact with the periphery of the make and break device and are respectively 30 connected to the rheostat R and the switch s. Between the rheostat and the switch there may also be located a hand operated means 46 for making and breaking the circuit which may be of the simple push-button 35 ton type, and may be manually operated for initially operating the pump for filling the intermediate fuel tank of a motor vehicle in the event of its being empty at the time it is desired to start the engine.

40 For use on automobiles, either as a fuel feeding pump or, as an oil or lubricating pump, the make and break device 40 may be located on any rotating shaft of the car, on the magnetic shaft or on a cam shaft for 45 example. The rheostat R, the switch s and hand operated make and break 45 preferably would be located on the dashboard of the car within easy reach of the driver's hand; the pump, which for either of these two uses, 50 particularly on automobiles, would be of about the dimensions shown in the drawings, and could in either or in both cases also be located on the dashboard either on the driver's side or on the engine side. In fact, 55 as later described, two pumps could be mounted together in the form of a duplex pump, one of them being used for fuel feeding and the other as the oil or lubricating pump. In this case each pump would have 60 its separate pipe connection. The fuel pump would have its T-member 16 connected on one side by a pipe connection 50 to the main fuel tank, and on the opposite side by a pipe connection 51 either direct to the carburetor or to a gravity tank, the lubri- 65

cating pump would have its pipe connections 50 connected to the main lubricating oil tank and its pipe connections 51 would branch out to the various parts of the car needing constant lubrication.

Below the T-connection member 16, I provide a cap 17 the purpose of which aside from use for inspection or cleansing of tube 14, may be to receive and hold, to trap so to speak, any small globules or particles of the mercury employed in the pump, (the purpose of the mercury being later explained), that may by heavy jars or bumps of the car, or otherwise be caused to spill into tube 14.

After the pump is set in place and all electrical connections made, the pump body, i. e., the solenoid tube is filled up to about three-fifths of its interior height with mercury M. Core 20 which is arranged to slid- 55 ingly fit into tube 11 is set into the tube and will slide therein until it comes into contact with the mercury into which it will sink until it has displaced a volume of the liquid metal the weight of which will be 90 equal to its own weight, the core shown in the drawing being of approximately the suitable length and being assumed to be the proper weight, the core thus normally projecting a distance out of the solenoid tube. The mercury is thus forced a certain distance upwards but as it cannot pass between the core 20 and the wall of tube 11, it rises in the interior of the core. If then 95 an electric current is passed through the solenoid this becomes energized and sucks, so to speak, the plunger core 20, downwards. This in turn presses upon the mercury which is forced to rise to a higher level and thus forces the air above it down tube 14 to the 100 T-connection 16 out of which it can only escape by passing through check-valve 18 into pipe 51. On breaking the electric current around the solenoid the downward pull 105 of the core ceases and the mercury, which is of nearly twice the specific gravity of the iron core, forces the core upwards and back 110 into the floating position it occupied before the energizing of the solenoid. The mercury on falling back to its former level leaves 115 behind it a partial vacuum, which is instantly refilled by air from the pipe connection 50 passing through check-valve 19. After a few initial manually effected solenoid energizing and de-energizing operations of the make and break, or push-button switch 46, all the air in the pipe connection 50 and tube 14, and nearly all that 120 above the mercury, will be expelled and replaced by liquid raised by the pump from 125 a lower to a higher level. These hand operations are of course made only at the start after the first setting up of the pump, for the purpose of priming the pump, or after 130 an inspection or cleaning operation of the

pump, after which the same functions will be performed by the rotary make and break device.

As before stated, some of the air above the 5 mercury column will not be expelled; such air, after the pump is fully primed and in operation being confined wholly in the upper part of the dome-like extension 22 of the iron core. This air will at each downward 10 stroke of the iron core and consequent upward rising of the mercury be compressed. This compression has two-fold effect, one of which will be to cause a smooth outflow of the liquid in tube 14, the other effect being 15 that immediately after the cutting off of the solenoid energizing current, by its distention pressure on the mercury column, the iron core 20 will be made to rise much quicker than it would if its upward push 20 was caused by the gravity pressure of the mercury column alone.

As it is very desirable, if not altogether necessary, that the total return stroke of the piston core 20 be made in a period of 25 time equal to that of its descending stroke, or in the period of interruption of the electric current in the solenoid, which period is determined by the width of the dielectric strips 43 of the rotary make and break device 30 and of course by the rotating speed of this device, I have recourse to the disposition as shown by the dash and dot lines in Fig. 1. This disposition consists in enclosing the upper part of the piston core 20 in an air-tight, dome-like cylinder 70 of non-magnetic metal, the inner wall of which serves, as near as possible, as a frictionless guide to flange 21 of the piston, and in the periphery of which are cut small notches for the passage 35 of the air between said flange and the top of the solenoid on the descending stroke of the piston, or vice-versa. By this disposition I obtain the following effects. On starting operation, and when the piston-core 40 is as far out of the solenoid as desired, the air-cock 71 on the top of the cylinder 70 is closed, and the amount of air in the cylinder is then equal to the cylinder's interior volume less the volume of all that part 45 of the piston core, flange included, extending above the solenoid. It is therefore obvious that when the piston-core descends into the solenoid the air-space in the cylinder will increase to as much in volume as is 50 the volume of the piston-core which has penetrated into the solenoid, and as cock 71 is closed and no outside air can replace the deficiency, the enclosed air must then expand and thus there is produced a slight 55 vacuum in the cylinder the direct effect of which will be a decrease in pressure on the piston-core, and hence an additional increase in the speed of its return stroke.

Referring to Fig. 2, which is a plan view 60 of the rotary mechanical make and break

device which may be mounted on any rotating shaft, preferably in proximity to the pump, but this means of operating the pump is not necessarily the only one. Any means, in fact, by which an intermittent electric current may be sent through the solenoid, may be resorted to. The pump as a single unit, or when joined with another to form a duplex pump as shown in Figs. 4 and 5, can be operated also by automatic means 75 such as shown in Fig. 4.

Pumps P and P' in Fig. 3 are of the same construction as that shown in Fig. 1 with the dome-like cylinder 70 by which, and by their pipe connection, they are coupled together to form what I term a duplex-pump. In Fig. 3 I show these pumps actioned by an automatic electric make and break device, generally denoted by E, but they can as well be operated by a rotary make and break device similar in principle of construction to that shown in Fig. 1 as will be shown later.

Domes 70 and 70' have in addition to the airclock 71 and 71' a horizontal cylindrical extension 72 and 72' facing each other on a same plane and axis. In each is located a piston 73 and 73' fitting closely yet slidingly the inner wall of their respective cylinders. The stems 74 of these pistons are connected together by means of a tubular union 74', the stems passing close fittingly through the hub of the cylinder caps 75 and 75' which close but not hermetically the outer end of the cylinders 72 and 72'.

These caps support above and below two distance brackets 76 and 76' which in turn support the automatic electric circuit make and break device E. The circuit make and break device is composed of the following parts. Two poles knife-switches 90 and 90'; 105 two swinging knife-bars 91 and 91'; a knife-bars distance link 93, and the make and break links 94 and 94' with their supporting slide-rods 95 and 95'. Switches 90 and 90' are insulatingly mounted on the distance bracket 76; knife-bars 91 and 91' are hingedly and swingingly mounted on the same bracket near their respective switches, the knives proper being insulatingly mounted on the swinging end of their bar, 110 each of which is linked to the other by the said distance-link 93. This link bar is of such a length that when one knife is engaged in its switch, the other knife is disengaged from the other switch. Links 94 and 94' are hinged together at one end by a common pin 96 which passes centrally through a longitudinal slot 96' out through the tubular union 74'; at their other ends 115 links 94 and 94' are hinged to the heads of the slide rods 95 and 95'. These rods pass slidingly through a central bore in their supporting brackets 76 and 76', helicoidal springs 97 and 97' around the rods, between their heads and their respective supporting

120

125

130

- bracket always tending to push the link-heads towards one another and away from the supporting brackets 76 and 76'. Their pressure is therefore exerted on the break-links 94 and 94', and through these, but more directly so by link 94 to the distance-link bar 93, and by this bar to the swinging knife-bars 91 and 91', to bring one of them into contact or engagement with its respective switch and to disengage the other from the other switch.

The operation of the whole make and break device is as follows: Piston-core 20 of pump P is supposed to have come to the 15 end of its downward stroke, and the electric current that energized its solenoid 10 to have been switched to the solenoid 10' of pump P', by the engagement of knife 91 with switch 90, and therefore piston-core 20' is at the start of its downward stroke and piston-core 20 at the start of its return upward, or back-stroke. As explained previously, the air in dome-cylinder 70' will become rarified on account of said downward stroke of core 20' and the air in dome-cylinder 70 will be brought back to its former atmospheric pressure. Both of these effects will simultaneously react with equal force on both pistons 73 and 73', on piston 73 with an outward pressure and on piston 73' with an inward suction, the effect being that the tubular union 74' will be pushed away from pump P towards pump P'. In its course it will come into contact 35 with pin 96 which passes through its slot 96'; pin 96 will force both links 94 and 94' towards the right, but as these links are respectively held by the hinge-heads of the slide-rods 95 and 95', these latter are forced 40 respectively upwards and downwards in their bore until links 94 and 94' have come with their vertical axis in line with that of the rods. At that moment a pin 98, fixedly set in link 94 and passing through a longitudinal slot 98' cut centrally in distance-link 93, comes in contact with the rightside end of this slot in readiness to push the link towards the right the moment pistons 73 and 73' in the continuance of their course 55 from left to right, have forced links 94 and 94' to pass to the right of their vertical axis when the springs 97 and 97' will react and push them with a snap-like action away from said vertical axis and thus, with a like 60 action, by means of pin 98 and distance-link 93, disengage knife 91 from switch 90, and engage knife 91' with switch 90'. By this operation the electric current is thus cut from solenoid 10' and switched over again to solenoid 10 with the consequent action on their core which produces an alternating pump action similar to the present well-known self-acting duplex-pumps.

The automatic circuit make and break device E just described is only one of the many

ways in which a rapid and instantaneous switch of current from one pump-solenoid to the other may be provided for actioning my pump in duplex installations. For example I may mention the well known snap-switch in use in lighting systems which may take the place of switches 90 and 90' and their knives. In fact any other such devices may be employed, but I prefer to employ the switch just described because I believe it to be entirely novel and its construction will be more suitable for the larger kind of pumps where a heavy electric current would be required for the operation of the pumps. It also may be noted that the rotary make and break shown in Fig. 1 could be replaced by this kind of automatic make and break device for the operation of my pump in single units, one single switch only being then necessary. If a pump P provided with the device E, only one switch would be employed, namely switch 90'. Piston-core 20 being on its upward return stroke would force piston 73 outwardly to push bars 94 and 94' over their dead line vertical axis and to close switch 90', when piston-core 20 would be started again on its downward stroke, rarifying the air in dome 70 and thus, sucking piston 73 inwardly would reopen switch 90', and so on until the current is cut off at the main switch. But, the preferred mode of operating my single pump is the one shown in Fig. 1, whenever and wherever it is to be operated in conjunction with machinery having shafts of suitable size and revolution speed for the adaptation on them of the device, or for driving a separately built one. Even for duplex pumps in similar circumstances a rotary make and break device would be my preferred form, and only in cases where no such rotating shafts are available may I have recourse to the make and break device E, the former being considerably cheaper to build, even for duplex pumps as can be seen in Figs. 5, 6 and 7, which show its construction and which is as follows. As in the case of the single pump rotary make and break device I use an insulating tube 40' set on a rotating shaft 41'. But instead of covering this tube with only one metal tube of the design as described, I use two tubes, 46 and 47, one on each end of the tube 40' and with their tongues 46' and 47' set at equal distance one from the other, and all the open spaces between them and the opposite tube or ring body filled up by strips 48' cut in relief on the periphery of tube 40', (see Fig. 7). For actuating the duplex pump three brushes are required, one brush 44' connected to one side of the source of power and two brushes 48 and 48' connected, one to one solenoid and the other to the other solenoid, the other ends of the solenoids be-

ing joined by a common return wire to the other side of the source of power. The current arriving by brush 44' is thus alternately shifted from one solenoid to the other as it passes from a tongue of one metal ring to the following tongue belonging to the other ring, with a certain length of time of complete current interruption in both solenoids. Thus in Fig. 7, the current arriving by brush 44' is transmitted to brush 48, then by the turning of the device, in either direction, brush 44' will pass over an insulation strip 43' cutting the current from the solenoid connected to brush 48, and on coming in contact with the metallic tongue appurtenant to metal ring 46, the current will be sent to the other solenoid by way of brush 48', and so on, vice-versa.

In the automatic make and break device shown in Fig. 3 the wiring is as follows. A wire W from one side of the source of power as represented by B' branches into two wires W and W' which are respectively connected to one of the two contact blades of switches 90 and 90'. A wire —w²— from the other blade of switch 90 leads to and is connected to one end not shown of solenoid 10', and a wire —w³— from the other blade of switch 90' leads to and is connected to the similar end also not shown of the solenoid 10, the other ends of the solenoids being joined together by a common return-wire W' leading to the other side of the source of power B' by way of switch S' and rheostat R'. As shown in Fig. 3 the current is therefore passing from B' by wire W and wire —w— to switch 90, and from this switch to solenoid 10' by wire —w²—, and from the solenoid 10' to main switch S' by wire W', and from this switch, supposedly closed, by rheostat R' back to B'.

Regarding the pipe connections of the duplex pump of Fig. 3, they are shown in Fig. 4. Both pumps have one common suction pipe 100 which divides into two branches by means of a T-member 101, one branch for pump P, the other for pump P'. Both branches are of identical construction and are composed of suction elbows 102 and 102', suction check-valves 103 and 103', of T-members 104 and 104' which may be both suction and delivery members, delivery check-valves 105 and 105', elbows 106 and 106' and a common delivery T-member 107 leading to the common delivery pipe 108. Pipes 109 and 109' respectively connect T-member 104 and 104' to T-members 16 and 16' below their respective pumps P and P', these T-members being similar to the one shown in Fig. 1 except that their outer opening is closed by a bushing 110 and 110'. The liquid to be pumped enters as per arrow —a— by pipe 100 into T-member 101, and through either of check-valves 103 and 103' to one or the other pump, alternately as the electric

current is shifted from one solenoid to the other, the liquid passing through pipes 109 and 109' first, in the direction towards the pump the piston-core of which is ascending while in the other pipe it flows in receding direction from the pump on account of the descending motion of the piston-core of the pump which forces it through the delivery check-valve of its branch and into the delivery pipe 107.

Having thus described my invention, it should be understood that there may be modifications thereof and variations therein without departing from the spirit of the invention, or exceeding the scope of the appended claims.

What I claim and desire to protect by Letters Patent is:—

1. In a pump, a hollow cylinder of non-magnetic material; coils around said cylinder; means operatively connected to said coils for alternately energizing and de-energizing the coils; a plunger of magnetic material in the cylinder and provided with a chamber in one end; the plunger being movable in one direction of reciprocation when said coils are energized; and mercury in said cylinder and chamber for moving the plunger in the cylinder in direction of reciprocation reverse to the first direction when said coils are de-energized.

2. A pump comprising a hollow cylinder of non-magnetic material, the cylinder being closed at one end and having an aperture through its closed end; coils around said cylinder; mechanism operatively connected to said coils for alternately electrically energizing and de-energizing the coils; a plunger of magnetic material in the cylinder having a chambered interior, the plunger being movable in one direction of reciprocation when said coils are energized; a pipe passing through said aperture of the cylinder and having an open end located in the chambered interior of the plunger; an inlet and outlet member connected to the opposite end of said pipe; an inlet valve and an outlet valve appurtenant to said member; and means free from actuation by electricity for moving the plunger in direction reverse to the first direction when the coils are de-energized.

3. A pump comprising a hollow cylinder of non-magnetic material, the cylinder being closed at one end and having an aperture through its closed end; coils around said cylinder; mechanism operatively connected to said coils for alternately electrically energizing and de-energizing the coils; a plunger of magnetic material in the cylinder having a chambered interior, the plunger being movable in one direction of reciprocation when said coils are energized; a pipe passing through said aperture of the cylinder and having an open end located in the

chambered interior of the plunger; an inlet and outlet member connected to the opposite end of said pipe; an inlet valve and an outlet valve appurtenant to said member; 5 and mercury in said cylinder and in said chambered interior of the plunger; the plunger when said coils are de-energized being movable in direction reverse to the first direction by return of the mercury to normal position after displacement by movement of the plunger in the first direction.

4. A pump comprising a hollow cylinder of non-magnetic material, the cylinder being closed at one end and having an aperture 15 through its closed end; coils around said cylinder; mechanism operatively connected to said coils for alternately electrically energizing and de-energizing the coils; a plunger of magnetic material in the cylinder 20 having a chambered interior and a chamber communicating with the chambered interior, the plunger being movable in one direction of reciprocation when said coils are energized; a pipe passing through said 25 aperture of the cylinder and having an open end located in the chambered interior of the cylinder adjacently to said chamber; an inlet and outlet member connected to the opposite end of said pipe; an inlet valve added 30 an outlet valve appurtenant to said member; and mercury in said cylinder and in said chambered interior of the plunger; there being inherent air in said chambered interior and in said chamber; the plunger 35 when said coils are de-energized being movable in direction reverse to the first direction by return of the mercury to normal position after displacement by movement of the plunger in the first direction and by said inherent air cooperating with the plunger. 40

normal position after displacement by movement of the plunger in the first direction and by said inherent air cooperating with the mercury; and a trap in said inlet and outlet member for receiving stray portions of the 70 mercury.

6. In a pump a tube of non-magnetic material; coils around said tube; an iron base for closing the tube at one end and having an apertured neck; a plunger of magnetic metal in said tube having a chambered interior and having an annular laterally extending flange near its upper end and a dome extension providing an air chamber communicating with said chambered interior; an open ended pipe secured at one end in said neck and passing through the lower portion of said tube and the chambered interior of the plunger to a point adjacent to said air chamber; mercury in said tube and in the chambered interior of the plunger and normally maintaining the plunger partially projected from said tube; and means for alternately electrically energizing and de-energizing said coils. 75 80 85 90 95

7. In a pump a tube of non-magnetic material; coils around said tube; an iron base for closing the tube at one end and having an aperture neck; a plunger of magnetic metal in said tube having a chambered interior and having an annular laterally extending flange near its upper end and an extension providing an air chamber communicating with said chambered interior; an open ended pipe secured at one end in said neck and passing through the lower portion of said tube and the chambered interior of the plunger to a point adjacent to said air chamber; mercury in said tube and in the chambered interior of the plunger and normally maintaining the plunger partially projected from said tube; rotatable means for alternately electrically energizing and de-energizing said coils; and means for rotating the first means.

8. In a pump a tube of non-magnetic metal; coils around said tube; an iron base for closing the tube at one end and having an apertured neck; a plunger of magnetic metal in said tube having a chambered interior and having an annular laterally extending flange near its upper end and an extension providing an air chamber communicating with said chambered interior; an open ended pipe secured at one end in said neck and passing through the lower portion of said tube and the chambered interior of the plunger to a point adjacent to said air chamber; mercury in said tube and in the chambered interior of the plunger and normally maintaining the plunger partially projected from said tube; rotatable means for alternately electrically energizing and de-energizing said coils; means for rotating the first means; and manually operable means

for starting operation of the first means independently of said means for rotating.

9. A pump comprising a tube of non-magnetic material; coils around said tube; an iron base for closing the tube at one end and having an apertured neck; a plunger of magnetic metal in said tube having a chambered interior and having an annular laterally extending flange near its upper end and an extension providing an air chamber 10 communicating with said chambered interior; an open ended pipe secured at one end in said neck and passing through the lower portion of said tube and the chambered interior of the plunger to a point adjacent to said air chamber; mercury in said tube and in the chambered interior of the plunger and normally maintaining the plunger partially projected from said tube; a branch pipe connected to the neck of the base of said tube and provided with a trap 15 for stray portions of mercury; a check-valve at the inlet of the branch pipe and a check-valve at the outlet thereof; and means for alternately electrically energizing and de-energizing said coils.

10. A pump comprising a tube of non-magnetic metal; coils around said tube; an iron base for closing the tube at an end and having an apertured neck; a plunger of magnetic metal in said tube having a chambered interior and having an annular laterally extending flange near its upper end and an extension providing an air chamber 30 communicating with said chambered interior; an open ended pipe secured at one end in said neck and passing through the lower portion of said tube and the chambered interior of the plunger to a point adjacent to said air chamber; mercury in said tube and in the chambered interior of the plunger and normally maintaining the plunger partially projected from said tube; a branch pipe connected to the base of the neck of 35 said tube and provided with a trap for stray portions of mercury; a check-valve at the inlet of the branch pipe and a check-valve at the outlet thereof; rotatable means for alternately electrically energizing and de-energizing said coils; and means for rotating the first means.

11. A pump comprising a tube of non-magnetic metal; coils around said tube; an iron base for closing the tube at one end and having an apertured neck; a plunger of magnetic metal in said tube having a chambered interior and having an annular laterally extending flange near its upper end and an extension providing an air chamber 55 communicating with said chambered interior; an open ended pipe secured at one end in said neck and passing through the lower portion of said tube and the chambered interior of the plunger to a point adjacent to said air chamber; mercury in said tube and in the 60

chambered interior of the plunger and normally maintaining the plunger partially projected from said tube; a branch pipe connected to the base of the neck of said tube and provided with a trap for stray portions 70 of mercury; a check-valve at the inlet of the branch pipe and a check-valve at the outlet thereof; rotatable means for alternately electrically energizing and de-energizing said coils; means for rotating the first 75 means; and manually operable means for starting operation of the first means independently of said means for rotating.

12. In a pump a solenoid the shell of which constitutes the pump cylinder and the 80 core of which constitutes the pump plunger; means for alternately energizing and de-energizing the solenoid, the core being moved in one direction when the solenoid is energized; and mercury in said shell for moving 85 the core in direction reverse to its first direction when the solenoid is de-energized.

13. In a pump, a solenoid, the shell of which constitutes the pump cylinder and the core of which constitutes the pump 90 plunger, said core having a chambered interior; means for alternately energizing and de-energizing the solenoid, the core being moved in one direction when the solenoid is energized; and mercury in said shell and in 95 said chambered interior for moving the core in direction reverse to the first direction when the solenoid is de-energized.

14. In a pump, a solenoid the shell of which constitutes the pump cylinder and the 100 core of which constitutes the pump plunger, said core having a chambered interior, there being inherent air in said interior; means for alternately energizing and de-energizing the solenoid, the core being moved in one direction 105 when the solenoid is energized; and mercury in said shell and in said chambered interior for moving the core in direction reverse to the first direction when the solenoid is de-energized, said inherent air cooperating 110 with the mercury for moving the core.

15. In a pump, a solenoid the shell of which constitutes the pump cylinder and the core of which constitutes the pump plunger, 115 a suction pipe in the shell-cylinder, the core-plunger when reciprocated cooperating with said pipe for producing suction in the pipe, the core-plunger being movable in one direction of reciprocation when the solenoid is energized, and means in the shell-cylinder 120 disposed around said pipe for moving the core-plunger in direction of reciprocation reverse to the first direction when the solenoid is de-energized.

16. In a pump, a solenoid the shell of which constitutes the pump cylinder and the core of which constitutes the pump plunger, 125 said core-plunger having a chambered interior at one end thereof, a suction pipe extending into the shell-cylinder and received 130

at one of its ends in said chambered interior, the core-plunger being movable in one direction of reciprocation when the solenoid is energized, and means for moving the core-plunger in direction of reciprocation reverse to the first direction when the solenoid is de-energized.

17. In a pump, A solenoid the shell of which constitutes the pump cylinder and the core of which constitutes the pump plunger, said core-plunger having a chambered interior at one end thereof, a suction pipe extending into the shell-cylinder and received at one of its ends in said chambered interior, the core-plunger being movable in one direction of reciprocation when the solenoid is energized, and means in the shell-cylinder disposed around said pipe for moving the core-plunger in direction of reciprocation reverse to the first direction when the solenoid is de-energized.

18. In a pump, a suction pipe, and a solenoid the shell of which constitutes the pump cylinder and the core of which constitutes the pump plunger, said core-plunger having a chambered interior at one end thereof for receiving the adjacent end of said pipe, said core-plunger when reciprocated cooperating with said pipe for producing suction in the pipe.

19. In a pump, a cylinder of non-magnetic material having an air rarifying chamber, coils around said cylinder; a plunger of magnetic material in the cylinder moved in one direction when said coils are energized, and means for moving the plunger in direction reverse to the first direction when said coils are de-energized, the plunger having an end portion extending into said chamber and movable therein when the plunger is moved, said end portion being adapted to permit passage of air from one portion of said chamber to another portion thereof when the plunger is moved.

45. 20. In a pump, a cylinder of non-magnetic material having an air rarifying chamber provided with open and closable means communicating with the atmosphere; coils

around said cylinder; a plunger of magnetic material in the cylinder moved in one direction when said coils are energized, and means for moving the plunger in direction reverse to the first direction when said coils are de-energized, the plunger having an end portion extending into said cylinder and movable therein when the plunger is moved, said end portion being adapted to permit passage of air from one portion of said chamber to another portion thereof when the plunger is moved.

21. In a pump, a cylinder of non-magnetic material having an air rarifying chamber provided with open and closable means communicating with the atmosphere; coils around said cylinder; a plunger of magnetic material in the cylinder moved in one direction when said coils are energized, and means for moving the plunger in direction reverse to the first direction when said coils are de-energized, the plunger having an end portion extending into said chamber and movable therein when the plunger is moved, said end portion being provided with a transverse annular flange permitting passage of air in said chamber between the portions of the chamber separated by said flange.

22. In a pump, a cylinder of non-magnetic material having an air rarifying chamber of dome shape provided with an air cock communicating with the atmosphere; coils around said cylinder, a plunger of magnetic material in the cylinder moved in one direction when said coils are energized, and means for moving the plunger in direction reverse to the first direction when said coils are de-energized, the plunger having an end portion extending into said chamber and movable therein when the plunger is moved, said end portion being provided with a transverse annular flange permitting passage of air in said chamber between the portions of the chamber separated by said flange.
